UNITED STATES PATENT OFFICE.

EARL B. HOUGH, OF CHICAGO, ILLINOIS, ASSIGNOR TO GUY M. PETERS, TRUSTEE, OF CHICAGO, ILLINOIS.

MOTION-TRANSMITTING MECHANISM.

Application filed September 11, 1920. Serial No. 409,560.

To all whom it may concern:

Be it known that I, EARL B. HOUGH, a citizen of the United States, residing at Chicago, in the county of Cook and State of Illinois, have invented a certain new and useful Improvement in Motion-Transmitting Mechanism, of which the following is a full, clear, concise, and exact description, reference being had to the accompanying drawings, forming a part of this specification.

My invention relates to motion-transmitting mechanism and is more particularly concerned with a motion transmitting mechanism which I have found so well adapted for use in the form of a lifting or dumping gear for lifting or tilting the bodies of dumping vehicles and the like that I have shown and described the invention in connection with a typical type of such vehicle. It is of course to be understood however, that I do not intend thereby to limit the invention to such use or purpose only as I am aware and contemplate various other adaptations of the invention.

It is the object of this invention to provide a simple and compact device for dumping truck bodies or the like.

To tilt a dumping body efficiently and dispose of the load therein, it is desirable that a variable lifting effort be provided, the maximum occurring at initial operation and gradually decreasing as the body raises to upper position. An inversely variable tilting movement should preferably accompany this, so that near the end of the stroke, the increasing lightness of the load may be taken into account to allow the body to accelerate in motion until the operation is completed. This, I accomplish by providing a pair of lever arms which form an extensible lifting connection between the body and frame and employing a cable to actuate the arms. The cable preferably is moved in a generally horizontal direction. This horizontal movement is translated into a vertical thrust for lifting the body first by a sheave for initial operation and thereafter by the swing of the lever arms. The cable is secured to the arm pivoted to the body at a point below the general line of movement of the cable. This has for its purpose the obtaining of a direct initial application of the force substantially vertically upon the load thereby securing a great lifting ad-

vantage. Different effective leverages are then provided through the lever arms, giving to the body an accelerated motion until the operation is completed. The cable moves in a generally horizontal direction which I term the general line of force.

A further feature of my invention is the provision of a lifting gear of simple, practical, substantial and inexpensive construction through which a highly effective and efficient application of the power to the load is had.

Other features and novel provisions of the invention will appear from the following detailed description and the claims taken with an inspection of the accompanying drawings in which I shall describe a specific embodiment of the invention in order to fully acquaint those skilled in the art with the nature and scope thereof.

In the drawings:

Figure 1 illustrates in side elevation a dumping truck with my improved lifting gear applied thereto, the body of the truck being shown in the horizontal position; and

Figure 2 is a view similar to Figure 1 showing the body of the truck tilted, in position for discharging the contents.

In that this invention is not concerned with the details of construction of the vehicle in itself, I will give just sufficient description of the form shown in the drawings as will enable those skilled in the art to clearly understand a particular embodiment of my invention in connection therewith.

Referring to the drawings, the dumping body 5 constituting the load the dumping mechanism must lift and which may be of any desired construction in so far as the present invention is concerned is pivotally mounted at 6 upon the running gear frame or bed 7 of the vehicle. A seat 8 of any suitable or preferred type is mounted upon the frame 7 of the vehicle just forward of the body 5, the forward end of the body extending when in the horizontal position, up immediately adjacent the rear of the seat as there need be no provision for the upright lifting structures, found in the prior art, therebetween.

The body 5 of the vehicle is tilted about the pivotal mounting 6 to discharge its contents by power applied through a motion transmitting mechanism or lifting mechanism designated generally by the reference

character 9. This motion transmitting mechanism or lifting mechanism 9 comprises an arm or link 10 pivoted at 11 to a suitable bracket 12, for example, suspended from the frame of the vehicle. The link 10 is pivotally connected at its opposite end with an arm 13, which arm 13 is in turn pivotally connected at its opposite end with the body 5 as shown at 14. The link 10 performs the function of guiding the lower end of the lifting arm 13 whereby the initial endwise movement of the arm 13 is secured without imposing substantially any force thereupon, the cable taking the load directly. Thereafter, the guiding arm 10 permits the arm 13 to form a strut between the load and said guide 10 in the nature of a toggle or cam to change the generally horizontal movement of the cable into a thrust upon the lifting arm. A cable 15 connected at one end with the arm or link 13 at a point 16 within the length of said arm leads up (Figure 1) and is trained over a sheave 17 mounted upon a substantially horizontal axis carried by the frame 7 of the vehicle from where it extends back beneath a sheave 18 likewise mounted upon a substantially horizontal axis carried by the frame 7. From beneath the sheave 18 the cable 15 extends to and is trained about a sheave 19 mounted upon a substantially vertical axis carried adjacent the rear or after end of the frame 7 and thence forwardly beneath the opposite side of the vehicle. The forward end of the cable 15 is attached to the forward end of a piston 20 reciprocable in a suitable cylinder 21 carried by the frame of the vehicle. I preferably employ one of the lifting mechanisms above set out adjacent each side of the vehicle, in which event connection is had between the forward ends of the two cables and a single piston 20 through an equalizing lever arm 22 as well understood by those skilled in the art. Assuming that the body 5 is in the position shown in full lines in Figure 1 a dumping operation is had as follows:

The piston 20 is moved forwardly by admitting a suitable motive fluid, either air or liquid, to the cylinder 21 as well understood by those skilled in the art. A substantially direct force or application of power is thereupon applied to the body 5 through the cable 15 and link 13 in the direction indicated by the arrow A (Figure 1) tilting the body about the pivotal mounting 6 into the position shown in dotted lines. This substantially direct initial application of power does not secure great tilting movement of the body 5 relative the distance of travel of the piston 20 but applies a relatively great force to the load to obtain a positive initial movement thereof. Upon further forward movement of the piston 20 the power is applied through the levers 10

and 13 arranged to secure great movement of the load relative the distance through which the power is thereafter applied, as evidenced by the relatively great change in inclination of the body 1 and relative slight change in position of the piston 20 in Figure 2 as compared with the dotted line position shown in Figure 1.

It will be apparent that while a substantially direct initial application of the force to the load is had, this initial lifting force is applied through a leverage, that is great lifting effect is had, by reason of the movement of the arm 10 about its pivot 11 and the gradual increase of the angle between the links 10 and 13. Thereafter the relatively great increase of the angle between the links 10 and 13 relative to the stroke of the piston provides for relatively great tilting of the body, with only a short application of power.

The rear board of the truck may be hinged and locked by a suitable snap lever to be automatically opened upon lifting the body of the proper angle although of course such provision is immaterial in so far as the present invention is concerned.

While the dumping operation of the body in the particular embodiment herein disclosed is effected by means of a reciprocable piston 20 it is to be understood that the source of power set out simply represents the type which I have found to be satisfactory, any other source of power may be employed such as a suitable winch or the like.

The features of providing a direct initial application of the power to obtain a relatively great force and consequently a positive initial movement of the load whereupon the power is applied through a leverage designed to secure great movement of the load relative the distance through which the power is thereafter applied are highly important aspects of my invention.

As hereinbefore set out the invention may appear in other forms and may be used for other purposes.

I claim:

1. In combination, a load, a source of power, a pair of lever arms and a flexible element secured to one of said lever arms for applying power from said source to said load through said arms, first substantially directly through one of said arms and thereafter through a leverage including said arms.

2. In combination, a load, a lifting arm for applying a substantially direct initial force to said load, a swinging arm providing with said first arm a toggle through which a force is thereafter applied to said load, a pair of sheaves, a flexible element trained between said sheaves and connected to said lifting arm below the adjacent sheave when in initial position and means for pulling on said cable.

3. The combination with the running gear of a vehicle of a dumping body pivotally mounted upon said running gear, a swinging arm carried by said running gear, a lifting arm between the dumping body and said swinging arm and a cable directly connecting said lifting arm to apply first, a substantially direct initial force to said dumping body through said lifting arm, said arms thereafter providing a leverage through which the force is applied to said body to lift said body to the desired inclination.
4. In combination, a frame, a superposed body, a pair of toggle arms linked together, a cable connected to said arms, means for pulling the cable in a generally horizontal direction, and means for translating the horizontal pull of the cable in a thrust substantially endwise along the line of the up- per arm for initial movement of the body.
5. In combination, a frame, a superposed load a lifting arm pivoted to the load, a guiding member connected to the frame and cooperating with the lower end of the lifting arm, a sheave secured to the frame and a horizontally movable cable trained over the sheave and secured to the lifting arm below the sheave.
6. In combination, a frame, a load, an unfolding linkage connecting said frame and load, a pulling cable, and guide means on said frame positioned to change the line of force of said cable, during a portion of the movement only.
7. In combination, a frame, a load, means for moving said load with respect to said frame, a pulling cable attached to said moving means to actuate the same, and stationary means for changing the line of action of said pulling cable during a portion of the movement only.
8. In combination, a frame, a load, means for moving said load with respect to said frame, a pulling cable attached to said moving means at a point having vertical dis-
- placement, and guide means intermediate the extreme positions of the point of attachment to engage the cable and change its line of force.
9. In combination, a frame, a load, means for moving said load with respect to said frame, a pulling cable attached to said moving means at a point having vertical displacement, and guide means positioned to engage the cable and deflect its final reach toward the vertical during the final portion of a downward movement.
10. In combination, a frame, a body pivoted thereto, a two-link linkage connecting a point on said body with the frame, both links being downwardly inclined when in folded position, a flexible tension member connected to the linkage and running to a relatively remote point in a generally horizontal direction, and guide means positioned intermediate the elevated and lowered positions of the tension connection, to contact the tension member and change its line of action toward the vertical during the lower portion of the movement.
11. In combination, a frame, a body pivoted thereto, a two-link linkage connecting a point on said body with the frame, both links being downwardly inclined when in folded position, a flexible tension member connected to the linkage and running to a relatively remote point in a generally horizontal direction, and guide means positioned intermediate the elevated and lowered positions of the tension connection, to contact the tension member and change its line of action toward the vertical during the lower portion of the movement, the frame link swinging into an upwardly inclined position before the vertical displacement of the tension connection moves the tension member away from said guide means.
- In witness whereof I hereunto subscribe my name this 9 day of Sept., 1920.
- EARL B. HOUGH.
